UNITED STATES PATENT OFFICE.

ROBERT M. KLIEMANT, OF BALTIMORE, MARYLAND.

TALKING-BOARD TABLE.

1,386,631.

Specification of Letters Patent. Patented Aug. 9, 1921.

Application filed June 9, 1920. Serial No. 387,616.

To all whom it may concern:

Be it known that I, ROBERT M. KLIEMANT, a citizen of the United States, residing at Baltimore, in the State of Maryland, have 5 invented certain new and useful Improvements in Talking-Board Tables, of which the following is a specification.

This invention relates to improvements in a talking board table and has for its object 10 to provide a table which is simple in construction and so arranged that a number of the tables can be nested together for the purpose of shipment. The invention consists of the novel construction and arrangement 15 of the parts hereinafter more fully set forth in the following specification and pointed out in detail in the appended claims.

In the accompanying drawing,

Figure 1 is a plan view of my invention.

20 Fig. 2 is a vertical longitudinal section of Fig. 1.

Referring to the accompanying drawing forming part of this specification and in which like reference numerals designate like 25 parts throughout the several views thereof, 1 designates the table which is provided with an annular bead 2 on the outer edge thereof, the said table has two projecting ends 3 opposite each other each provided 30 with a leg 4. The said table is also provided with the legs 5 on the opposite side thereof and a number of depressions 6 at each side for the purpose of accommodating the ends

of the fingers of the parties using said table. The legs 4 and 5 are integral with the said 35 table, being drawn down therefrom and are cone shaped and hollow so that the tables can be fitted one upon the other with the legs of each table each projecting into those of the table adjacent thereto. By this construction 40 it will be seen that a number of the tables can be packed in a very small space for the purpose of shipping. The legs 4 at each end of the table serve as pointers to indicate the letter, figure or other character 45 on the board upon which it is used.

Having thus described my invention what I claim is,

1. A talking board table having an annular bead on the edge thereof, integral cone 50 shaped hollow legs projecting from each end and from the sides thereof.

2. A talking board table having cone shaped legs projecting below each end thereof and below the side thereof, and a number 55 of depressions around the side of said table board between said legs.

3. A talking board table having an annular bead on the edge thereof, integral cone shaped legs projecting below each end of 60 said table and below the opposite sides thereof, and a number of depressions extending around both sides of said table between the said legs.

In testimony whereof I affix my signature. 65]

ROBERT M. KLIEMANT.
